UNITED STATES PATENT OFFICE.

WILLIAM J. BAUMBERGER, OF DAVENPORT, IOWA, ASSIGNOR TO MICRO MACHINE COMPANY, OF BETTENDORF, IOWA, A CORPORATION OF IOWA.

WORK SUPPORT.

Application filed April 6, 1925. Serial No. 21,056.

This invention relates to improvements in work holders for grinding machines and the like.

In positioning work upon a machine, preparatory to grinding cylinder walls and the like, it is customary to provide a fixture which is associated with the machine so that the work can be positioned in desired relation with the grinder. Generally such fixtures include a frame which can be bodily adjusted transversely and longitudinally relative to the grinder, and a pair of parallel jaw members, which are supported by the frame, between which the work is held. It is desirable, with this type of fixture, that the jaws can be adjusted in a vertical plane so as to accommodate various sizes of work, as well as to present the work in different elevations to the grinding wheel. Due to the weight of the work, and to the manner in which the jaw members are now mounted, the jaw members often get out of parallel relation and also tilt even when parallel, both of which conditions are deleterious to good grinding.

An object of my invention is to provide a work holder having vertically adjustable jaw members which are mounted so that they will remain continuously in parallel relation and in the same horizontal relation in any position of adjustment.

A further object of my invention resides in providing a work holder having jaw members which can be adjusted separately, or together, in a vertical plane, and which will remain in parallel relation and in the same horizontal relation.

Still another object of my invention resides in the provision of mechanism which can be operated to adjust jaw members of a work holder, either separately or together, in a vertical plane.

These and other objects and the invention itself will appear in the following specification.

In the accompanying drawings,

Fig. 1 is a front elevation of a work holder embodying my invention, fragmentary parts being shown in section.

Fig. 2 is an end elevation of the same.

Fig. 3 is a section taken on line 3-3 of Fig. 4 showing mechanism for adjusting the jaws.

Fig. 4 is a plan view of the work holder.

Fig. 5 is an end elevation, partially in

section, of the lower jaw member showing the shaft for adjusting the same.

Fig. 6 is a section taken on line 6-6 of Fig. 5.

Referring now to the drawings by characters of reference, 10 represents a fragmentary portion of the machine table which is reciprocable relative to the grinder. Such table is provided with a dove-tail recess in its bottom so that it can be adjustably secured to the movable portion of the machine bed. The fixture is secured to the table and is arranged to hold work in the path of the grinder and in desired relation therewith.

A platform 11 is mounted upon the table 10 and is secured thereto by bolts 12 and 13 in a conventional manner. The upper face of the platform is provided with a transversely extending dove-tail recess 14, so that the work holder portion of the fixture can be 75 slidably associated therewith.

A base frame 15 is seated upon upstanding ribs 16 of the platform 11, and is provided with a depending dove-tail tongue 17 which extends into the recess 14 and is secured against the side walls thereof by a gib 18. A screw shaft 19 extends transversely relative to the machine table and is rotatably carried in bearings depending from the base frame. The shaft extends through a threaded bearing 20 secured to the platform, and a handle 21 is provided at one end of the shaft so that it can be manually rotated to move the base frame bodily transversely upon the platform and 90 across the path of the grinder.

The base frame is formed with a pair of upstanding parallel standards 22 which carry the work to be operated upon by the grinder. The standards are provided with vertically extending flanges which have parallel bearing faces 23 across which a pair of jaw members 24 and 25 extend and are mounted so that they bear thereagainst. Vertically extending retaining bars 26 are secured in spaced relation adjacent the faces 23 of the standards by bolts 27. The heads of the bolts are countersunk in the bars and extend through the bars and the flanges of the standards being secured by nuts 29. The space intermediate the bars and the faces 23 provides vertically extending guideways to prevent lateral displacement of the jaw members, and to permit them to be moved in a vertical plane.

A shaft 30 is rotatably carried by apertured bearing portions at each end of the lower jaw member 25, and a gear 31 is keyed to the ends of the shaft adjacent each end of the jaw member. One of the gears is provided with an irregularly shaped stub shaft 32 upon which a hand crank can be applied to rotate the shaft and the gears. Racks 33 are secured to each side of the vertical flanges of the standards 22, and the teeth are arranged so that they will be engaged by the gears 31. By rotating the shaft 30 the lower jaw member will be moved bodily in a vertical plane, because of the engagement of the gears with the racks, and therefore the horizontal position of the lower jaw member will remain similar in any position of vertical adjustment.

A bearing housing or bracket 34 is secured by bolts 35 upon the top of each standard 22 and projects beyond the faces 23 above the upper jaw member 24. Each bracket is provided with a removable cap section 36, and a vertically extending bushing 37 is rotatably carried by each bracket. The bushings are threaded to engage the screw shafts 38 which extend therethrough, and are secured at their lower ends to the jaw member 24 by any suitable means such as a pin 38', indicated in Fig. 3. A gear 39 is keyed to each of the bushings 37 and meshes with worm gears 40 within the bracket housings, which gears 40 are secured to a shaft 41 carried in bearings in the housings. One end of such shaft projects beyond a housing and is formed to receive a crank by means of which it can be manually rotated.

The upper jaw member is thus suspended adjacent each end from the screw shafts 38. By rotating the shaft 41, the gears 40 will rotate the gears 39 and the bushings to which they are keyed, and thereby move the screw shafts and the upper jaw member bodily in a vertical plane. The gearing is arranged so that the screw shafts operate alike, and thus the upper jaw member is always maintained in the same horizontal relation in any position of vertical adjustment. The jaw members are arranged in parallel relation, and they will remain in such relation, due to their mounting, in any position of vertical adjustment. It will be seen that either jaw member can be adjusted independently by the manual operation of the mechanism associated therewith for such purposes.

A releasable connection is provided between the jaw members to secure them together in various desired spaced relations to accommodate different sizes of work. Links 50 are secured, by studs 51 at one end, to the ends of the lower jaw member, and they project upwardly substantially the length of the standards adjacent the ends of the upper jaw members. The links are provided with vertically extending slots 52, and studs 53

extend through such slots and can be screwed into apertures in the ends of the upper jaw member to clamp the links therewith. By unscrewing the studs 53, the jaw members can be adjusted vertically independently. When the links are clamped to the upper jaw member by the studs 53, the jaw members can be moved as an integral structure in a vertical plane when the mechanism for adjusting the upper jaw member is operated. When the jaw members are secured in spaced relation by the links, the mounting of the screw rods 38 make it impossible to operate the mechanism for adjusting the lower jaw member.

With the above described adjustments, various sizes of work can be held between the jaw members by making the independent vertical adjustments, and when the work is secured between the jaw members, unitary vertical adjustments can be made to place the work in the desired plane for the proper operation of the grinding wheel.

It will be seen that with the construction described, it is impossible for the jaws to get out of parallel relation or to vary in their horizontal relation in any vertical position of adjustment, either separately or in unison.

It will be further seen that with the construction described the jaw members can be readily and easily adjusted bodily in a vertical plane, thereby saving time in positioning work in the holder for a grinding operation.

Various changes can be made in the structure described herein without departing from the spirit of my invention and the scope of what I claim.

What I claim is:

1. A fixture for supporting work in the path of a tool comprising a frame having upstanding standards, a pair of parallel jaw members carried by said standards, said jaw members being adjustable relatively and together in a vertical plane, independent mechanism for bodily adjusting each of said jaw members, said members remaining continuously in a horizontal plane, and releasable means for securing said jaw members together in adjusted relation.

2. A fixture for supporting work in the path of a tool comprising a frame, a pair of parallel jaw members carried by said frame and adjustable independently in a vertical plane, a rotatable shaft carried by the lower jaw member, racks carried by said frame, and gears secured to said shaft positioned to mesh with said racks for maintaining said lower jaw member in the same horizontal relation in any position of vertical adjustment, and releasable means for connecting said jaw members in spaced vertical relation, the rotation of said shaft when said connecting means is released causing said lower jaw member to move bodily in a vertical plane.

3. A fixture for supporting work in the path of a tool comprising a frame, a pair of vertically adjustable jaw members, brackets secured to said frame, adjustable means carried by said brackets for suspending said upper jaw member, a means releasably connecting said jaw members, means for preventing lateral displacement of said jaw members from said frame, and means for 10 maintaining said jaw members continuously in parallel relation.
4. A fixture for supporting work in the path of a tool comprising a frame, a pair of vertically adjustable jaw members, brackets secured to said frame having threaded bearings therein, threaded shafts extending through said bearings in said brackets, said shafts being secured to the upper of said jaw members, manually operable means for rotating said shaft to bodily vary the vertical position of said upper jaw member, releasable means connecting said jaw members, and means for preventing lateral displace- 15 20
- ment of said jaw members from said frame, and means for continuously maintaining 25 said jaw members in parallel relation.
5. A fixture for supporting work in the path of a tool comprising a frame, a pair of parallel jaw members slidably mounted with said frame, said jaw members being adjustable vertically independently and in unison, links secured to one of said jaw members, and releasable means for securing said links to the other of said jaw members in any relative parallel spaced relation of said jaw members, separate mechanisms for moving each of said jaw members independently in a vertical plane when said links are released, one of said mechanisms moving both of said 30 35 40 jaw members in a vertical plane in unison and the other mechanism being inoperative when said jaw members are secured together by said links.

In testimony whereof I affix my signature.

WILLIAM J. BAUMBERGER.
